John A. Diederich*
ATTORNEY.

UNITED STATES PATENT OFFICE.

B. JAY ANTRIM, OF PHILADELPHIA, PENNSYLVANIA.

FIRE AND BURGLAR ALARM.

SPECIFICATION forming part of Letters Patent No. 278,386, dated May 29, 1883.

Application filed February 27, 1883. (No model.)

To all whom it may concern:

Be it known that I, B. JAY ANTRIM, a citizen of the United States, residing in the city and county of Philadelphia, State of Pennsylvania, have invented a new and useful Improvement in Fire and Burglar Alarms, which improvement is fully set forth in the following specification and accompanying drawings, in which—

Figure 1 is a partial side elevation and vertical section of an alarm embodying my invention. Fig. 2 is a top or plan view, partly sectional in line *x x*, Fig. 1. Fig. 3 is an end view, partly in elevation and partly sectional in line *y y*, Fig. 2. Fig. 4 is a top view of the lower section of the barrel portion of the alarm. Fig. 5 is a longitudinal section of a modification. Fig. 6 is a top view thereof. Fig. 7 is a section of a portion of a modification.

Similar letters of reference indicate corresponding parts in the several figures.

My invention consists of improvements in the automatically-operated fire and burglar alarm for which Letters Patent of the United States No. 268,597 were granted to me on the 5th day of December, 1882.

Referring to the drawings, A represents a holder, which is constructed of sections *a a*, channeled on their inner faces, forming barrels B to receive fire-crackers, cartridges, or other explosives, A', said sections being properly clamped or connected.

C represents spring-pressed plungers or pistons, which are fitted within the barrels and adapted to be discharged by the explosives in said barrels; and D represents a channel within the holder, extending at a right angle to the barrels and communicating therewith by means of ducts *b*, formed in the holder. In either section *a a* are vents *c*, which communicate with the barrels at places above or below the plungers C, and are closed by the plungers when in their normal positions, it being seen that when the plungers are operated the vents are uncovered, thus permitting the escape of the created gases, the springs C' afterward restoring the plungers to their normal positions.

In the holder are also vertical ducts *c'*, each of which communicates with a duct, *b*, and communicating with said ducts *c'* are nipples E, which are secured to the upper side of the

holder, said nipples being adapted to hold percussion-caps, which, when exploded, will cause the ignition of fuses G in the ducts *b*, said fuses also communicating with an explosive or burning material in the channel D. Overhanging each nipple is a gravitating or spring-pressed hammer, H, which is guided in a suitable framework, J, so that when it descends it strikes a nipple beneath it, the upper end of the stem of the hammer having a spring-catch, K, which engages with a bar, plate, or lug, L, on the frame J, the nose of said catch being so disposed that it may be engaged by a gravitating or spring-pressed piece, M, and thus thrown off from the lug L, the hammer being thereby released and permitted to descend. The throw-off piece M is held clear of the catch K by a rod, cord, or wire, *d*, which is connected with an elbow or other lever suitably mounted in an apartment, a cord, *d'*, being also connected with said lever and reaching to some locality from whence an alarm may be sounded, the release of said cord *d'* causing the release of the throw-off piece M and the consequent operation of the hammer and discharge of the cap on the nipple.

Formed or secured to the outer end of the holder are lugs P, on which are supported caps Q, to which are attached rods, cords, or wires R, reaching to a distant alarm, whereby when the explosive in barrels are ignited by the fuses G, due to the discharge of the caps, and the plungers C are operated, the caps Q are forced from the lugs P, the effect whereof is to permit the rising of the rods, cords, or wires R, thus causing the operation of some distant alarms or the dropping of said caps on the floors of the apartments, thus sounding alarms, the noise of the explosion of the percussion-caps and explosives also creating alarms.

Instead of the caps Q, I may employ levers Q, (see Figs. 5 and 6,) which, when forced back by the plungers, operate distant alarms, which are connected with said levers by rods, cords, or wires, the levers Q being pivoted to the holder, wall of the apartment, or other suitable support.

The holder may be formed with as many barrels as there are rooms, apartments, or places to protect, it being evident that a single barrel may be employed, which, however,

will be provided with all the appurtenances of a many-barreled holder.

In the event of fire the proper cord, d' , will be released, either automatically if the flames reach the same, or it may be cut or ignited by hand; and the same provision may exist in the case of the connection d , which may be made of some inflammable material; or either connection may be attached to a door, window, &c., so as to be released by the entrance of burglars, the effect in any case being to permit the descent of the throw-off piece and cause the disengagement of the catch K , and consequent rapid movement of the hammer, whereby the cap under the latter is struck and the alarm is sounded. When the fuse beneath the struck cap is ignited, fire is communicated to the material in the channel D , and thus the remaining fuses are ignited and all of the barrels discharged, so that an alarm is sounded in each room, apartment, or place where alarm mechanism is located, these operations being quickly accomplished owing to the immediate ignition of the fuse beneath the cap which is struck, and the rapid ignition of all other fuses.

S represents a metallic case, which is secured to a wall or other suitable place in a room, and contains a fuse or cord, S' , of any desired thickness, and of such nature or preparation as to readily ignite and burn apart, thus releasing the connections of the throw-off piece and causing an alarm, said case S being so located that in case of fire in the room the flames will readily reach an opening in said case, and thus ignite the fuse or cord within the same. Said case and contents may, however, be of the form of a thermostat, which, when the temperature of the room reaches a certain height due to fire, will act to liberate the connections of the throw-off piece and cause the alarm.

If desired, the nipples may communicate directly with the channel D , so that the material therein will simultaneously ignite all of the fuses G and discharge the several barrels, it being evident that said nipples may support

percussion-caps, fulminates, primers, &c.; or, in lieu of the nipples, I may employ firing-pins to be struck by the hammers H and explode fulminates, which may be applied to blank cartridges or located in the ducts b or channels D —a feature desired in wet or damp localities—a form of such arrangement being shown in Fig. 7.

The caps Q may be substituted by balls or weights, which may be hung on the end of the holder or fitted in the ends of the barrels, or connected with bolts to lock or unlock doors, &c.

The hammers H may be made to slide vertically on the frame J , as shown, or pivoted thereto so as to swing toward and against the nipples or pins, without, however, producing different results from those stated.

Having thus described my invention, what I claim as new, and desire to secure by Letters Patent, is—

1. A hammer suspended by a catch, a weight adapted to strike said catch in falling and release said hammer, and a string or other easily-severed support for said weight, in combination with a barrel containing explosive material, and a percussion-cap arranged below said hammer and in communication with said explosive material, so as to ignite the latter when the said hammer falls.

2. A case containing explosive material, a cord arranged to be broken by the explosion thereof, a weight suspended by said cord and its attachments, and a hammer suspended by a catch which is arranged to be released by the falling of said weight, in combination with a barrel containing explosive material and a percussion-cap arranged to be exploded by the falling of said hammer and to ignite said explosive material, substantially as set forth.

B. JAY ANTRIM.
